ENGINE

Andre J. Meyer, Detroit, Mich., assignor to Continental Motor Corporation, Detroit, Mich., a corporation of Virginia

Application June 15, 1931, Serial No. 544,422

14 Claims. (Cl. 123—81)

This invention refers to internal combustion engines and refers more particularly to engines of the sleeve valve type.

In the sleeve valve types of engines it is generally customary to provide a cylinder head for each cylinder of the engine, the cylinder head being of the re-entrant type in which the portion of the cylinder head forming the combustion chamber depends within the upper portion of the cylinder and is spaced therefrom to provide an annular recess or pocket which accommodates the movement of one or more sleeve valves. Difficulty has been experienced in such structures in properly sealing the sleeve pocket against the escape of gases from the combustion chamber resulting in loss of pressure and power and also resulting in the accumulation of carbon, rust and other substances generally referred to as sludge, to the general detriment of the engine and particularly those parts associated with the sleeve pocket.

It is an object of my invention to provide an improved sleeve pocket structure which will effectively over-come the aforesaid difficulties. A further object of my invention resides in the provision of an improved sealing means for the sleeve pocket, which sealing means is capable of manufacture and assembly at relatively low cost and which will maintain an efficient operation over long periods of use.

It is a further object of my invention to provide an improved sealing structure for an engine of the general type referred to hereinabove, wherein by reason of a selection of metals and also by reason of the constructions hereinafter more fully described, my improved sealing means will function in an improved way over a wide range of engine temperatures.

Further objects and advantages of my invention will be apparent as this specification progresses, reference being made for purposes of illustration to the accompanying drawing in which:

Fig. 1 represents the vertical sectional view through a typical cylinder of the engine showing the sleeve pocket structure.

Fig. 2 is a like view illustrating a slightly modified form of my invention.

Fig. 3 is a detail sectional enlarged view of the sleeve pocket structure shown in Fig. 1, and

Fig. 4 is a detail view along the lines 4—4 of

Fig. 3.

In order to illustrate my invention I have shown a sleeve valve engine of the single sleeve type generally known as the Burt-McCollum engine in which a single sleeve usually operating between

the piston and cylinder is given a combined axial

reciprocation and oscillation by any suitable well known means whereby a point on the sleeve traces a closed curve path in performing the usual valving cycles of the engine. In the drawing reference character A represents the engine cylinder block and 10 is one of the cylinders thereof, the cylinder being provided with the usual intake and exhaust ports 11 and 12 respectively, the usual intake and exhaust manifolds 13 and 14 being associated with the respective ports. Within cylinder 10 is located the sleeve valve 15 having intake and exhaust ports 16 and 17 respectively for cooperation with the cylinder ports 11 and 12 as the sleeve is moved as aforesaid by any suitable actuating device such as is illustrated at 18. Within the sleeve 15 is located the piston 19 adapted to operate the connecting rod 20 which extends as usual to the engine crankshaft (not shown). It will be understood that the parts as thus far described form no part of my invention in themselves as these may be of any suitable construction and arrangement. For illustration it will be apparent that the features of my invention are readily adaptable to engines having more than one sleeve or in connection with engines of the single sleeve type in which the sleeve is operated by a movement other than the combined type of movement referred to above.

Reference character B represents a structure adapted to close the cylinder, such structure constituting a cylinder head having the generally cylindrical portion 21 depending within the upper end of the cylinder and spaced within the cylinder walls to form a sleeve pocket 22 for accommodating movement of the upper end of sleeve valve 15. According to my invention as illustrated in Fig. 1, the portion 21 of the cylinder head B is provided with an annular recess 23 near the upper end thereof, this recess being adapted to receive the inwardly extending annular shoulder 24 which is formed at the upper edge of a sealing element 25. The element 25 is preferably of cylindrical endless form circumferentially and is fitted closely in engagement around the exterior cylindrical walls of the cylinder head portion 21, the sealing element preferably engaging the cylinder head under tension. In order to secure this tension I heat the cylindrical element and place the same under close fit on the cylinder head whereby when the sealing element cools it will be under an initial tension resulting in a tight fit with the cylinder head. The rib on shoulder 24 is preferably formed after the sealing element has been placed in position and this shoulder is conveniently formed by spinning the upper end 110

of the sealing element into the recess 23. In the form shown in Figs. 1 and 3 it will be noted that the sealing element 25 extends downwardly below the lower edge of the cylinder head portion 21 whereby an annular portion 26 of the sealing element is exposed to the pressure developed in the combustion chamber 27. Also in these figures the cylinder head portion 21 is provided with a series of axially spaced circumferential grooves 28 for the purpose of providing a labyrinth seal against escape of gases from the combustion chamber 27.

In the operation of the device as thus far described the sealing element 25 is fitted securely 15 with the cylinder head portion 21 and forms a bearing for the sleeve valve 15. When explosion takes place in the combustion chamber 27 the pressure developed thereby will act against the portion 26 of the sealing element 25 tending to 20 very slightly expand the same and prevent the escape of gases toward the sleeve pocket between the sleeve valve and sealing element 25. Since the latter element is engaged by shoulder 24 with the cylinder head portion 21 it will be apparent 25 that there can be no escape of gases into the sleeve pocket between cylinder head portion 21 and sealing element 25. In order to further assist against a tendency for passage of gases and accumulation into the sleeve pocket I have provided a labyrinth 30 structure or grooves 28. In order to prevent the sealing element 25 from being displaced circumferentially under the influence of the oscillatory component of the sleeve valve, I preferable provide the diametrically opposite points in the groove 35 23, a recess 29 extending inwardly of the groove and the shoulder portion 24 of the sealing element is deflected at 30 into the recess 29 thereby securing the sealing element against rotative displacement. Referring to Fig. 2 similar reference characters indicate corresponding parts as 40 described in connection with the other figures of the drawing and it will be noted that in Fig. 2 the sealing element 17' does not extend below the effective lower edge of the portion 21' of cylinder head B', since I have found that with such 45 an arrangement as illustrated I have obtained very excellent and improved sealing and anti-sludge results. In Fig. 2 also, I have omitted the grooves 28 of Fig. 1 since in many cases these 50 may be readily dispensed with in obtaining the objects of my invention.

As a further feature of my invention I have provided a construction which will effectively seal the sleeve pocket structure under varying conditions of temperature, thus by way of illustration 55 I preferably formed the cylinder block A and cylinder head B of cast iron and the sleeve valve 15 of steel tubing. The sealing element 25 is preferably formed of brass which in addition to its 60 excellent bearing characteristics with the sleeve valve provide the additional advantage of compensating for the differences in expansion between the cast iron cylinder head and steel sleeve. This feature of my invention is very important 65 since it provides for efficient sealing of the sleeve pocket during the time when the engine is warming up and also prevents tendency for sludge accumulations at various conditions of temperature under which an engine is normally subjected. 70 The present sealing element 25 is preferably relatively thin in cross section so that it has a certain amount of spring or resiliency under the influence of pressure developed in combustion chamber 27 as aforesaid.

75 What I claim as my invention is:

1. In an engine, a cylinder, a structure closing the cylinder and having a portion depending within and spaced from the cylinder, valve means operable in the space provided between said structure and cylinder, a sealing element associated with said structure subjected to the pressure developed during the engine power stroke for sealing said space, said element projecting below said structure, and means for supporting said sealing element in engagement with said valve means. 80

2. In an engine, a cylinder, a structure closing the cylinder and having a portion depending within and spaced from the cylinder, valve means operable in the space provided between said structure and cylinder, and a sealing element associated with said structure subjected to the pressure developed during the engine power stroke for sealing said space, said element being secured at its upper edge to said structure. 90

3. An engine of the sleeve valve type comprising in combination, a cylinder, a cylinder head providing a combustion chamber and depending within said cylinder, sleeve valve means between the cylinder head and cylinder, a cylindrical sealing element intermediate the cylinder head and sleeve valve means, and means for supporting said element in engagement with said sleeve valve means, said element projecting below the cylinder head to provide an outwardly expanding portion subjected to pressure developed in the combustion chamber. 100

4. An engine of the sleeve valve type comprising in combination, a cylinder, a cylinder head providing a combustion chamber and depending within said cylinder, sleeve valve means between the cylinder head and cylinder, and a cylindrical sealing element intermediate the cylinder head and sleeve valve means, said sealing element being fixed at its upper end and disposed in engagement with said sleeve valve means. 110

5. An engine of the sleeve valve type comprising in combination, a cylinder, a cylinder head providing a combustion chamber and depending within said cylinder, sleeve valve means between the cylinder head and cylinder, and a cylindrical sealing element intermediate the cylinder head and sleeve valve means and disposed in engagement with said sleeve valve means, said sealing element being fixed at its upper end and being 120 free at its lower end.

6. An engine of the sleeve valve type comprising in combination, a cylinder, a cylinder head providing a combustion chamber and depending within said cylinder, sleeve valve means between the cylinder head and cylinder, and a cylindrical sealing element intermediate the cylinder head and sleeve valve means and disposed in engagement with said sleeve valve means, said sealing element being fixed at its upper end and being 130 free at its lower end, said lower end being exposed to the combustion chamber.

7. An engine of the sleeve valve type comprising in combination, a cylinder, a cylinder head providing a combustion chamber and depending within said cylinder, sleeve valve means between the cylinder head and cylinder, a cylindrical sealing element intermediate the cylinder head and sleeve valve means, and means for supporting said element in direct engagement with said 140 sleeve valve means, said cylindrical element being continuous circumferentially.

8. An engine of the sleeve valve type comprising in combination, a cylinder, a cylinder head providing a combustion chamber and depending with- 150

- in said cylinder, sleeve valve means between the cylinder head and cylinder, and a cylindrical sealing element intermediate the cylinder head and sleeve valve means, said cylindrical element being continuous circumferentially and engaging the cylinder head under tension. 5

9. An engine of the sleeve valve type comprising in combination, a cylinder, a cylinder head providing a combustion chamber and depending within said cylinder, sleeve valve means between the cylinder head and cylinder, and a cylindrical sealing element intermediate the cylinder head and sleeve valve means, said element being shrunk on said cylinder head. 10

15 10. An engine of the sleeve valve type comprising in combination, a cylinder, a cylinder head providing a combustion chamber and depending within said cylinder, sleeve valve means between the cylinder head and cylinder, and a cylindrical sealing element intermediate the cylinder head and sleeve valve means, said cylinder head having a groove adjacent the upper edge of said element, said element having a rib seated in said groove. 20

25 11. An engine of the sleeve valve type comprising in combination, a cylinder, a cylinder head providing a combustion chamber and depending within said cylinder, sleeve valve means between the cylinder head and cylinder, and a cylindrical sealing element intermediate the cylinder head and sleeve valve means, said head having a recess, said element having a portion thereof deflected into said recess to secure the element to the head. 30

12. An engine of the sleeve valve type comprising in combination, a cylinder, a cylinder head providing a combustion chamber and depending within said cylinder, sleeve valve means between the cylinder head and cylinder, and a cylindrical sealing element intermediate the cylinder head and sleeve valve means, said sealing element being secured at its upper edge and depending therefrom in engagement with the cylinder head but radially movable therefrom. 80

13. In an engine, a cylinder, a structure closing the cylinder and having a portion depending within and spaced from the cylinder, valve means operable in the space provided between said structure and cylinder and relatively movable with respect to said structure, and a sealing element disposed directly intermediate said structure and said relatively movable valve means for sealing said space, said element being secured at its upper edge to said structure. 85

14. In an engine, a cylinder, a structure closing the cylinder and having a portion depending within and spaced from the cylinder, sleeve valve means operable in the space provided between said structure and cylinder, and a sealing element associated with said structure and disposed in said space in normal engagement with the head and in direct yielding engagement with said sleeve valve means, said sealing element having an inner face arranged to project beyond the inner extremities of said head and thereby being subjected to the pressure developed during the engine power stroke for sealing said space. 90
